WARDROBE-TRUNK.

1,371,612.

Specification of Letters Patent. Patented Mar. 15, 1921.

Application filed November 23, 1918. Serial No. 263,383.

To all whom it may concern:

Be it known that we, JOHN W. ESPENLAUB, WILLIAM H. NORTHELL, and FRED W. GOEDEKE, citizens of the United States, residing at Evansville, in the county of Vanderburgh and State of Indiana, have invented a new and useful Wardrobe-Trunk, of which the following is a specification.

This invention has reference to wardrobe trunks, and its object is to provide a trolley fixture for supporting the garment hangers used in the trunk.

In accordance with the invention there is provided a metal frame for attachment about three sides of what constitutes the upper end of the trunk in use; the frame being interior to that portion of the trunk constituting the wardrobe part. The metal frame carries posts to which are secured telescoping slides 20 of peculiar construction permitting the hangers to be moved without interference along the slides, whether pushed in or extended, and permitting the extension or retraction of the slides with both members 25 thereof at all times at one level. At the same time the movable member of the slide is securely held in the fixed member of the slide against any but longitudinal movements with the top portions of both members 30 of the slide exposed in side by side relation.

The invention will be best understood from a consideration of the following detailed description taken in connection with the accompanying drawings forming part of this specification, with the understanding, however, that the invention is not confined to any strict conformity with the showing of the drawings but may be changed and modified so long as such changes and modifications mark no material departure from the salient features of the invention as expressed in the appended claims.

In the drawings:

Figure 1 is a perspective view of the slide carrier having slides thereon as applied to a wardrobe trunk, the view including a single garment hanger and the slides being partially projected.

Fig. 2 is a plan view of the structure shown in Fig. 1 but showing a greater number of garment hangers on the slides.

Fig. 3 is a section on the line 3—3 of Fig. 2 but drawn on a larger scale and omitting the garment hangers.

Fig. 4 is a section on the line 4—4 of Fig. 3.

Fig. 5 is a perspective view of the movable member of a telescoping slide.

Fig. 6 is a perspective view of the companion or fixed member of the telescoping slide.

Fig. 7 is a perspective view of one of the corner brackets of the slide support or frame.

Fig. 8 is a perspective view of another bracket used in conjunction with the corner bracket for carrying a fixed member of the slide.

Referring to the drawings, there is shown a portion of the body member 1, cover 2 and drawer section 3 of a wardrobe trunk. These parts need no special description since they may be of ordinary construction and the drawings omit the usual trimmings and other details employed in such trunks. The body member 1 is of a character to be stood upright when in use as a wardrobe and one side of the body member is open to be closed when necessary by the drawer member 3, and the cover member 2 when moved onto the upper end of the body member completes the closure.

Secured to the upper end of the body member on the inner face thereof is a three-sided frame 4 which may be conveniently formed of strap metal bent into shape, the frame 4 comprising a single elongated side 5 and two ends 6. In the particular showing of the drawings the corners of the frame 4, where the side 5 and ends 6 join, are made angular as indicated at 7, and secured to the inner face of the frame at the corners 7 are angle posts 8 which may also be made of strap or sheet metal appropriately shaped and riveted or otherwise secured at the angles 7 and to the side 5 and appropriate end 6. Secured to the sides 6 of the frame 4 near the open side of the body member 1 are upstanding brackets 9, each with an extension 10 terminating in a curved seat 11 spaced away from the sides 6 of the frame 4 toward the interior of the body member 1.

Piercing that portion of each post 8 extending along the side 5 is a perforation 12 of generally oval shape but having the upper end 13 contracted in diameter and provided with a shoulder 14 extending axially of the oval while the other end of the oval at a

point about midway of the length of said oval is returned toward the longitudinal center line of the oval, as shown at 15, until it meets the shoulder 14. The result is that the 5 perforation 12 is of oval configuration for about half its length while the remainder of the length of the perforation is of semi-oval configuration.

Having one end traversing the perforation 10 12 is a similarly shaped tubular member 16 open throughout along one side, as shown at 17, the tube 16 having a return lip 18 corresponding to the shoulder 14 and when the tube is inserted in the perforation 12 the 15 lip 18 is in engagement with the shoulder 14. On the opposite side of the tube 16 from the lip 18 is another lip 19 projecting toward the side of the tube provided with the lip 18 and curved in conformity with the return 20 portion 15 of the perforation 12 so as to be lodged in such part of the perforation 12. A tongue 20 is formed at one end of the tube 16 and is bent outwardly away from the tube to bear against the outer face of 25 the post 8 and is riveted or otherwise secured to said post to support the tube 16 in a substantially horizontal position, when the trunk is in the upright operative position as a wardrobe, with the tube 16 in spaced 30 parallel relation to the corresponding side 6 of the frame 4 but elevated above said frame by the post 8 and bracket 9. The outer end of the tube 16 is supported in the seat 11 and is secured to the bracket by 35 rivets 21 or in any other suitable manner. A tongue 22 is struck up from the bracket 9 against the lip 19 of the tube 16 so as to stiffen the tube where supported by the seat 11.

40 Contained within the tube 16 in telescoping relation thereto is another tube 23 of generally oval cross section and provided with a longitudinal slot 24 which is narrower than the slot 17 of the inner tubular 45 member 16. The tube 23 is shaped to fit snugly yet slide freely in the tube 16 and has a longitudinal inwardly directed rib 25 to bear against the inner face of the lip 18. The other side of the tube 23 is bent away 50 from that side containing the rib 25 so as to project or bulge through the passage or slot 17 of the tube 16 and rises to the height of the tube 16 where provided with the lip or flange 18. Such part of the tube 23 is 55 indicated at 26 and is provided with an in-turned flange 27 directed toward the lip or flange 18 into close relation thereto. The inner and outer tubes have a maximum width equal to each other or approximately 60 so. The two contiguous portions of the tubes 16 and 23 between which the lip 18 extends complete a rounded supporting surface for the hook-shaped end 28 of a garment hanger 29, which latter may be of

customary construction and hence requires 65 no special description.

The outer end of the tube 16, that is the end remote from the post 8, is beveled, as indicated at 30, and the inner end of the tube 23 is similarly beveled, as indicated 70 at 31, so that these two ends of the members 16 and 23 composing the slides present no abrupt shoulders or corners liable to catch on the hangers resting on the hanger slides. The tube 23 is prevented from turning ax- 75 ially by the rib 25 and flange 27 which engage with the lip 18.

Traversing the inner end of the tube 23 is a pin 32 which may be conveniently made as a screw pin but which serves as a stop 80 pin which will engage the tongue 22 when the movable member 23 of the slide is drawn out to its full extent. This arrests the outward movement of the member 23 at a sufficient distance from the outer end of the 85 fixed or supporting member 16 of the slide to hold the telescoping member 23 in a rigid projected position without sagging. The pin 32 also helps to prevent axial turning of the tube 23. At the outer end of the 90 movable member or tube 23 is a head 33 serving as a stop for the garment hangers and also as a manipulating head.

The construction is such that while the 95 movable member of the slide telescopes into the fixed or housing member of the slide, those parts of the two slide members which constitute the upper portions thereof are on a level one with the other when the trunk is in position to act as a wardrobe and the 100 two members form substantially equal supports for the garment hangers on opposite sides of the center line of the slides without presenting any impediment of any kind to the free movement of either the garment 105 hangers or the movable members of the slides into and out of the body member of the trunk.

The frame 4 may be made of material of such width as to be flush with the top of 110 the body 1 or may rise to a greater height so as to project a short distance, say half an inch above the top of the body member 1, so as to enter the top 2 and stiffen the structure when the top 2 is closed.

115 What is claimed is:—

1. In a wardrobe trunk, a slidable support for garment hangers, comprising tubular slotted members in telescoping relation, with one member within and having a side 120 extension projecting laterally through the other member and expanded and returned toward the first member to form part of the support for the garment hangers, said support being divided to substantially equal 125 extents between the two telescoping members of the slide.

2. An extensible slide for wardrobe trunks,

comprising an outer slotted tube and an inner telescoping tube, means holding the outer tube at one end to the trunk, a bracket supporting the outer tube at its other end, 5 said bracket having a seat for the outer tube and a tongue to help maintain the tube in its seat, and a stop member on the inner tube projecting through the slot of the outer tube and contacting with said tongue when 10 the telescoping tube is drawn out to its full extent.

3. A supporting slide for garment hangers of wardrobe trunks, comprising a tubular member circumferentially incomplete 15 to provide a side opening through the tube and another circumferentially incomplete tubular member telescoping into the first tubular member and provided with a side extension projecting through the side opening 20 in the first tubular member and shaped in conformity to and brought to a level with the exterior of the first-named tubular member in opposed matching relation thereto, whereby the two telescoping members provide 25 substantially equal support to the garment hanger.

4. A support for garment hangers of wardrobe trunks, comprising telescoping members each of tubular form, one of the 30 members being fixed and the other telescoping into and out of the first-named member, the first tube being of generally oval form in cross section and incomplete circumferentially, one end of the oval being contracted 35 in width with the tube provided with a longitudinal, substantially centrally located in-turned flange, and the other tube being of incomplete oval cross section of a size to house snugly and freely in the first tube and 40 provided with a longitudinally disposed extension projecting through the incomplete side of the first-named tube and expanded laterally to a width substantially equal to that of the first-named tube and then re- 45 turned toward the longitudinal flange of said first-named tube into close relation thereto and substantially on a level with the corresponding portion of the first-named tube, whereby the two tubes provide a telescoping support for garment hangers with 50 each presenting substantially the same area of support to the garment hangers.

5. An extensible slide for wardrobe trunks, comprising an outer tubular member 55 and an inner telescoping member, the outer member having a longitudinal slot in its side, the inner member bulging out through said slot and being larger on its upper side than on its lower side, a bracket supporting the outer member at one end, said bracket having a seat to receive said outer member, and a tongue to hold the outer tube in its seat, said tongue curving around the lower edge or lip of the slotted outer member and

engaging with the inner member below the 65 bulging portion.

6. An extensible slide for wardrobe trunks, comprising an outer slotted tube and an inner telescoping tube which is also slotted, a lip formed on the outer tube and 70 extending into the slot of the inner tube to prevent axial movement of the latter, said inner tube having stop means and supporting means for the outer tube engaging with the stop means when the inner tube is withdrawn, said outer tube being beveled at its outer end and said inner tube being beveled at its inner end.

7. An extensible slide for wardrobe trunks, comprising two telescoping tubes, 80 the outer tube being secured to the trunk and being open on one side, an inturned lip bordering one edge of the tube where open, the inner tube having an inwardly directed rib bearing against the inner face of said 85 lip, and also having a section projecting through the open part of the outer tube and having an inturned flange in substantial contact with the outer face of the lip, whereby the two tubes are incapable of relative axial 90 movement, and said tubes have their upper portions on a level one with the other and form substantially equal supports for garment hangers.

8. An extensible slide for wardrobe 95 trunks, comprising two telescoping tubes, the outer tube being secured to the trunk and being open on one side, an inturned lip bordering one edge of the tube where open, the inner tube having an inwardly directed 100 rib bearing against the inner face of said lip, and also having a section projecting through the open part of the outer tube and having an inturned flange in substantial contact with the outer face of the lip, said inner tube 105 where contained by the outer tube having its walls in snug contact therewith, the projecting part being extended away from the opposite wall so that the inner tube has a maximum width equal to that of the outer 110 tube.

9. In a wardrobe trunk, a three-sided frame having angular parts at the corners thereof, angle posts secured to the angular parts, said posts having each a perforation 115 of generally oval shape provided with an inwardly directed shoulder, tubular members secured to the frame and fitted at one end into the perforations, and an inner telescoping member carried by each of the tubular 120 members.

10. An extensible slide for wardrobe trunks, comprising two telescoping tubes, the outer tube being secured to the trunk and being open on one side, an inturned lip 125 bordering one edge of the tube where open, the inner tube having an inwardly directed rib bearing against the inner face of said lip,

and also having a section projecting through the open part of the outer tube and having an inturned flange in substantial contact with the outer face of the lip, said inner tube 5 where contained by the outer tube having its walls in snug contact therewith, the projecting part being extended away from the opposite wall so that the inner tube has a

maximum width equal to that of the outer tube.

In testimony that we claim the foregoing as our own, we have hereto affixed our signatures.

JOHN W. ESPENLAUB.
WILLIAM H. NORTHELL.
FRED W. GOEDEKE.
